UNITED STATES PATENT OFFICE.

FERDINAND S. RUTTMANN, OF PLAINFIELD, NEW JERSEY.

STEAM-ENGINE.

SPECIFICATION forming part of Letters Patent No. 410,451, dated September 3, 1889.

Application filed October 12, 1888. Serial No. 287,916. (No model.)

To all whom it may concern:

Be it known that I, FERDINAND S. RUTTMANN, of Plainfield, in the county of Union and State of New Jersey, have invented certain new and useful Improvements in Steam-Engines, of which the following is a specification.

This invention relates to an improved rotary engine which may be operated with an elastic or non-elastic medium, and in which the steam-cylinders and pistons are located within the fly-wheel and rotated with the same, the rotary motion being imparted to said fly-wheel and cylinders by straps connecting a stationary eccentric sidewise of the fly-wheel, through which the main shaft is passed, with the cross-heads of the piston-rods of the steam-cylinder.

The invention consists of certain details in the construction of a rotary engine in which the cylinders, pistons, piston-rods, cross-heads, and cross-head guides are located radially to the center shaft of the machine and within the plane of the fly-wheel, as will be fully described hereinafter.

In the accompanying drawings, Figure 1 represents a side elevation of my improved steam-engine, partly in section. Fig. 2 is a vertical longitudinal section on lines *x x*, Fig. 3 is an elevation of the opposite side of the engine. Fig. 4 is a plan of the same. Figs. 5, 6, and 7 are vertical transverse sections respectively on lines *y y*, *z z*, and *k k*, Fig. 2, drawn on a larger scale; and Figs. 8 and 9 are horizontal sections respectively on lines *c c* and *l l*, Figs. 6 and 7.

Similar letters of reference indicate corresponding parts.

Referring to the drawings, A represents a fly-wheel, the hub of which is secured to a main shaft S, that turns in bearings *a a* of standards A' A'', located at opposite sides of the shaft.

On the hub of the fly-wheel A, and within the same, are arranged radial cylinders F, preferably three, so as to produce a uniform motion of the engine. The cylinders F are located equidistantly from each other and alternate with the radial arms of the fly-wheel A. The outer ends of the cylinders F are connected with the rim of the fly-wheel A by means of parallel guide-rails *ff*, which are

securely bolted to the end flanges of the cylinders and to the fly-wheel, and which serve to guide the cross-heads *f' f'*, to which the piston-rods *f''* of the pistons F are pivoted, as shown clearly in Fig. 2. The pivot-pins *f''* of the cross-heads *f' f'* are extended laterally beyond the rim of the fly-wheel A, and are connected to strap-rods H, which are applied by circular straps or bands *h* to a stationary eccentric C, which is formed integral with the supporting-standard A'. The main shaft S passes through the stationary eccentric C and extends at both sides of the standards A' A'', so as to be adapted for transmitting power from either end of the shaft.

To the opposite standard A'' is applied the steam-chest D, with its supply and exhaust pipes, the reversing-gear, and the cut-off valve. The steam-chest D is provided with a transverse partition *d*, which divides it into two compartments or chambers T and U. The chamber T is provided with a steam-supply pipe *t*, and the chamber U with an exhaust-pipe *u*. The cylinders F communicate by passages *i* in the fly-wheel A and main shaft S and port *i'* with an annular channel L, that is arranged in the standard A'' around the shaft S, said channel being divided into two semicircular parts by fixed abutments *m m*, of which one is located around the upper part and the other around the lower part of the shaft S.

A cylindrical reversing-valve O is located above the upper abutment *m* and provided with ports *r* and *s*, which connect the annular channel L, respectively, with the chambers T and U of the steam-chest D. The ports *v* and *s* are arranged at right angles to each other and communicate with the channel L at opposite sides of the upper abutment *m*. The lower part of the exhaust-port *s* is made wide enough so as to communicate with the upper end of the annular channel L and with the exhaust-channel Q, as shown in Fig. 6.

The annular channel L communicates, further, at both sides of the lower abutment *m* by means of ports *p p* with an annular exhaust-channel Q, which is concentric to the channel L and arranged to communicate at its upper part with the exhaust-port *s* in the reversing-valve O and at the lower part at each side of the lower abutment *m* with sep-

arate exhaust-passages $p' p'$, each of which is provided with stop-valves. (Not shown in the drawings.)

In the annular channel L are arranged in-
5 termediately between the abutments $m m$ longitudinal cut-off bars $b b$, which are connected to semicircular guide-plates b' , that are guided in recesses b^2 of the supporting-standard A². The bars $b b$ form with the 10 plates b' the cut-off valve of the engine. One of the guide-plates b' is provided at its circumference with cogs or teeth, which mesh with a worm-screw b^3 , that is applied to a spindle b^4 , provided with a hand-wheel b^5 at 15 the outer end, as shown in Figs. 4 and 5. For the purpose of changing the positions of the cut-off valve $b b'$ the spindle of the worm-screw b^3 may also be connected with a suitable governor (not shown in the drawings) 20 for the purpose of automatically regulating the speed of the engine to any desired degree by correspondingly setting the cut-off valve $b b'$.

The spindle of the reversing-valve O is 25 provided at its outer end with a lever O', by which the valve O may be turned on its axis and the position of the ports r and s relatively to the chambers T and U and channels L and Q changed. This action reverses 30 the engine by converting the chamber T into the exhaust-chamber and the chamber U into the live-steam chamber.

When live steam is admitted successively into the cylinders F, the pistons F' and the 35 cross-heads f' of the piston-rods are moved radially in outward direction, so that by the action of the connecting-rods H, which are strapped to the stationary eccentric C, rotary motion is imparted to the fly-wheel A, main 40 shaft S, and the parts connected with the same. The steam passes from the live-steam chamber T and the port r of the reversing-valve O into the annular channel L, and from the same through the port i' and the longitudinal channel i of the shaft S into the cylinders F. Live steam is supplied until the 45 port i' has passed the first longitudinal bar b of the cut-off valve. After the port i' has passed the lower abutment m the steam is exhausted from the cylinder F through that 50 part of the annular channel L which is located below the transverse bar b at the opposite side of the shaft S and through the exhaust-channel Q and exhaust-port s of the reversing-valve O to the exhaust-chamber U and 55 passed out through the exhaust-pipe u . After the port i' has passed the bar b of the cut-off valve the exhaust-steam passes directly through the annular channel L above said 60 bar to the exhaust-port s , chamber U, and exhaust-pipe u .

When the engine is to be run continuously in one direction without requiring to be reversed, the exhaust-steam may be passed 65 through the pipes p' , the valves of which may be opened, so as to give a freer exhaust. The advantages of my improved rotary

engine are, that by locating the cylinders, pistons, piston-rods, cross-heads, and cross-head guides within the plane of the fly-wheel a very compact construction of the engine is obtained, while hardly any packing of the parts is required. Rotary motion is produced by the strap-connection of the cross-heads with the stationary eccentric, 75 which is located outside of the fly-wheel. All the parts can be readily inspected and the engine be quickly reversed and worked at different degrees of speed by the cut-off arrangement, so that the same is adapted 80 to a wide range of application in the arts.

Having thus described my invention, I claim as new and desire to secure by Letters Patent—

1. The combination of a central shaft, radial cylinders mounted on said shaft, a fly-wheel concentric to said shaft, guide-rails connecting the cylinders and fly-wheel, cross-heads connected to the piston-rods of the cylinders, a stationary eccentric surrounding 90 the shaft, and strap-rods applied to the stationary eccentric outside of the plane of the fly-wheel and pivoted to the cross-heads, substantially as set forth.

2. The combination of supporting-stands having bearings, a central shaft supported on said bearings, a stationary eccentric surrounding said shaft and forming a part of one of the standards, radial cylinders mounted on said shaft, a fly-wheel concentric to said shaft, guide-rails connecting the cylinder and fly-wheel, cross-heads connected to the piston-rods of the cylinders, and strap-rods applied to the stationary eccentric and pivoted to the cross-heads outside 105 of the plane of the fly-wheel, substantially as set forth.

3. The combination, with a central shaft having longitudinal channels and ports, of cylinders mounted radially on said shaft, a fly-wheel extending around said cylinders, guide-rails connecting the cylinders and fly-wheel, cross-heads for the piston-rods, a stationary eccentric surrounding said shaft, strap-rods pivoted to the cross-heads and applied to said eccentric, a steam-chest having a transverse partition forming a live-steam and an exhaust chamber, annular steam-channels around the shaft, abutments in said channels, and a cylindrical reversing-valve 120 having ports at right angles to each other, substantially as set forth.

4. The combination of a central shaft having longitudinal channels and ports, cylinders mounted on said shaft, a fly-wheel concentric to said shaft, guide-rails connecting the cylinders with the fly-wheel, cross-heads for the piston-rods guided in said rails, a stationary eccentric located outside of the fly-wheel and surrounding the central shaft, 130 strap-rods pivoted to the cross-heads and applied to the eccentric, a steam-chest having a transverse partition forming a live-steam and exhaust chamber, annular steam-supply

and exhaust channels communicating with the ports and channels in the shaft, a cylindrical reversing-valve having steam-supply and exhaust ports at right angles to each other, abutments located in the annular supply-channel at the upper and lower part of the same, a cut-off valve having longitudinal bars located in the steam-supply channel, and mechanism for setting said cut-off valve, substantially as set forth.

In testimony that I claim the foregoing as my invention I have signed my name in presence of two subscribing witnesses.

FERDINAND S. RUTTMANN.
